Design No. 3,807, dated December 28, 1869.

DESIGN FOR A BADGE.

The Schedule referred to in these Letters Patent and making part of the same.

To all whom it may concern:

Be it known that I, ABRAHAM DEMAREST, of the city of New York, in the county of New York, and State of New York, have originated and designed a new Subject for a Badge, of which the following is a full, clear, and exact description, reference being had to the accompanying specimen, making part of this specification.

First, I claim, as original, the design, in high relief, composed of the figure of Liberty, on one side of which is a Union soldier, clasping hands with a loyal sailor, with hand on his breast, denoting mutual pledges to

protect and provide for the orphan children of fallen comrades, shown in the group, and to teach them loyalty to the Union and the flag for which their fathers died.

Of this design, in combination with the emblems on the five points of the star, denoting the different arms of the service, in combination with the star, as an original design of a badge, I claim to be the originator.

ABRAHAM DEMAREST.
